UNITED STATES PATENT OFFICE.

EDGAR F. HOWE, OF EL CENTRO, CALIFORNIA.

ENGINE.

1,150,768.

Specification of Letters Patent. Patented Aug. 17, 1915.

Application filed June 12, 1914. Serial No. 844,698.

To all whom it may concern:

Be it known that I, EDGAR F. HOWE, a citizen of the United States, and a resident of El Centro, in the county of Imperial and 5 State of California, have invented a new and Improved Engine, of which the following is a full, clear, and exact description.

My invention relates to engines of the rotary type, and has reference more particularly to the internal combustion type of engine in which a turbine is actuated by the explosion impulses from a chamber provided with means for varying the capacity of said chamber, independently of the rotation of said turbine.

The invention also relates to the provision in a rotary engine of a rotary compressor with means for restoring the explosive chamber to its normal volume after explosion has taken place, also for scavenging the chamber, supplying the chamber with fuel mixture, and to explode the mixture in the chamber by compressed air.

The invention further relates to the provision for supplying radially directed explosive impulses to the turbine element, whereby said impulses are simultaneously applied to all parts of the turbine.

An object of the invention is to provide 30 a simple, compact and inexpensive rotary engine and turbine combined.

With the above and other objects in view, the nature of which will more fully appear as the description proceeds, the invention 35 consists in the novel construction, combination and arrangement of parts as herein fully described, illustrated and claimed.

In the accompanying drawings forming 40 part of the application similar characters of reference indicate corresponding parts in all the views, and

Figure 1 is a side elevation of an engine embodying my invention, with the accessories therefor; Fig. 2 is a longitudinal section on the line 2—2 of Fig. 3; Fig. 3 is a section on the line 3—3 of Fig. 2; Fig. 4 is a longitudinal section through the explosion chamber, showing the details of the mechanism for actuating the piston; Fig. 5 is a section on the line 5—5 of Fig. 4, showing the detailed structure of the valve controlling the device for actuating the piston; and Fig. 6 is a perspective view of the cam action for operating the valve controlling said device 55 for the piston.

Referring to the drawings, 5 represents

the casing of the stator, preferably formed of three parts, of which 6 is a section open at the ends, and thereat provided with heads 7 and 8. The head 7, in the center thereof 60 is provided with a co-axial cylinder 9 projecting exteriorly and interiorly of said head. The inner end of the cylinder is preferably closed, as shown at 10, while the outer end of the cylinder is closed by a head 65 11 secured thereto in any suitable way. Positioned within the cylinder 9 is a piston 12 which is bell-shaped and provided with an integral, annular extension 13 for better guiding the piston. A piston rod 14 projects through the head 11 and at the end thereof is provided with a spider member 15 rigidly secured thereto.

The portion of the cylinder 9 within the casing 5 is provided with a series of slots 16 75 leading from the interior of the cylinder into the head 7. The said slots are preferably adjacent the wall of the head, and normally closed by the piston 12 under the action of the compressed air in the pockets 17 80 engaged by the plungers 18 which are carried by the alining arms of the spider 15. The piston 12 is also provided in its annular extension or sleeve 13 with a series of openings 19 adapted to register with the slots 16 85 when the fuel mixture supplied by the valve 20 carried by the spider is exploded in the cylinder 9. When the said openings 19 of the piston 12 are in registry with the slots 16 90 (see Fig. 3), the exploded gases will find an outlet therethrough from the cylinder 9 into the head 7. The exterior lateral surface of the cylinder 9, which is within the head 7, is provided with a series of stationary vanes 21, preferably integral with the cylinder 95 and the head 7. These vanes are adapted to guide the exploded gases coming from the cylinder 9, into the head, so as to impinge on the vanes 22 disposed about the vanes 21 and carried by a rotor 23 provided in the 100 cylindrical part 6 of the stator.

The rotor 23 is rigidly secured to a shaft 24, one end of which bears in the closed end 10 of the cylinder 9, and the other end projects through the head 8 whereat a driven pulley 25 is provided. The rotor 23 preferably is provided with a concentric recess engaging part of the cylinder 9 and whereat a roller bearing 26 is provided. The shaft 24 carries also a second rotor 23', similar to the rotor 23 but without wings, and which, if desired, may be made integral with the

rotor 23. A thrust ball bearing is preferably provided between the said rotor 23' and the head 8.

The rotors 23 and 23' are each provided with a peripheral groove 27, in which operates a movable abutment 28 dividing said groove into two parts. The cylindrical part 6 at each side of said abutments is provided with pipes 29 and 30 communicating with said grooves 27 of which 29 forms an air inlet and 30 an air outlet. Each of the abutments 28 is furnished with a rod 31 projecting through the casing, whereat a coil spring 32 is engaging a bracket 33 whereby said abutments are normally maintained in engagement with the groove 27.

The grooves 27, with the abutments 28 and the inlets and the outlets for said grooves form compressors when the rotors 23 and 23' are in motion. The air is compressed in the grooves 27 as the point 34 of the groove approaches the abutments 28. Thus the compressed air is forced through the outlets 30 into storage tanks 35 and 36 of which the storage tank 35 is for the compressor formed by the rotor 23, and the storage tank 36 is for the compressor formed by the rotor 23'. Check valves 37 are provided on the pipes 30, preventing back flow after the point 34 of the grooves has passed the air outlet 30. The point 34 in the two grooves 28 of the two compressors formed by the rotors 23 and 23' are preferably diametrically opposite, and of which the compressor formed by the rotor 23 is preferably able to compress the air to a higher point, therefore the air tank 35 contains air of higher pressure than the air tank 36. The lower air pressure may be obtained from the tank 35 by providing a pressure reducing valve, in which case the compressor 23' and the tank 36 may be dispensed with.

The air tank 35 is connected to the pockets 17 by a conduit 50. At the said pockets reciprocating valves 39 are provided which control the supply of air to the pockets and therefore the displacement of the piston 12. Each of the plungers 18 is provided with an articulating arm 40 which is adapted to participate in all the movements of said plungers. The articulating portion 41 of the arms 40 is maintained in position by a spring 42. The end of said articulating portion of the arm 40 is enlarged and beveled as shown at 43, forming an inclined plane which causes the roller 44 provided at the end of the valve 39 to ride up the arm when the arm moves toward the valve, and to displace the valve, to cut off the supply of air to the pockets from the conduit 38 and to open said pockets to the atmosphere by means of the opening 45 provided in the casing of the valve 39. This movement of the arms toward the valve 39 takes place when an explosion is produced in the cylinder 9, and therefore the communication of the pockets with the atmosphere reduces the resistance to the movement of the piston 12 toward the openings 16 provided in the cylinder 9. As soon as the roller 44 passes the enlarged portion at the end of the arm 40 it again establishes communication of the pockets with the conduit 38, thus restoring the piston to its normal position. This engagement is not interrupted by the returning movement of the articulated portion of each arm 40.

The low pressure air tank 36 is connected to the fuel tank 46 whereby the fuel from the tank 46 is driven through the conduit 47 to the valve casing 48, wherein the valve 20 is operated. The said valve is provided with a cup 49 having a perforated bottom 50, which cup is adapted to come into alignment with the conduit 47 when the piston 12 under the action of the explosion has reached its limit position, that is, when the openings 19 of the piston are in registry with the openings 16 of the cylinder 9. Thus the cup will be instantaneously filled with fuel, and as the piston returns to its normal position the valve 20 is moved and the cup 49 comes into alignment with a branch of the conduit 50, and also with the opening 51 forming the inlet into the cylinder 9. The air from the conduit 50, which is under high pressure, forces the fuel from the cup, into the cylinder, in a fine spray, that is, highly disintegrated, an explosion takes place due to the air being raised to a high temperature by the compression thereof.

To perfectly scavenge the cylinder 9 after the explosion has taken place, the cylinder is provided with a valve controlled inlet 52 adapted to admit air into the cylinder from the conduit 38. The valve 52 is under spring tension, tending to open said valve, and the same is prevented by a sliding cam 53, which is connected to the spider 15 and adapted to move when the piston 12 is moved. The cut out portion 54 of the cam 53 permits the valve 52 to open and this takes place when the piston 12 has reached its end position under the action of the explosion, that is when the openings 19 of the piston are in registry with the openings 16 of the cylinder 9. It will be remarked that the valve 52 is only open for a short period of time, so that the pressure therein falls substantially to that of the tank 36, because the said valve 52 is closed after the openings 19 and 16 are out of registry.

The part of the cylinder 9 with which the piston 12 is not coming in contact is preferably lined with a refractory substance so as to reduce injury to the cylinder. A pipe 56 forms the outlet for the products of combustion coming from the cylinder 9 after the same has been passed through the vanes as previously stated.

The registry of the openings 16 and 19 permits the explosive gases to move radially from the cylinder 9 into the head and act on the vanes 22 of the rotor, thus causing the rotation of the same. The explosion of the gases within the cylinder 9 as previously stated, will force the piston away from the head 11 of the cylinder 9, causing the spider to move therewith, and therefore the plungers 18 with the actuating arms provided thereon will be moved and will actuate the valves 39; this movement of the valve 39 will reduce the resistance to the exploded gases, which moves the piston 12 toward the end 10 of the cylinder 9. When the openings 16 and 19 are in registry, the valve 52 will admit air for scavenging the cylinder, and simultaneously, the valves 39 will be restored to their normal positions, by the fall of the roller 44 from the enlarged portion of the arm 41, consequently air pressure will be applied to the plungers 18 and the piston 12 driven to its normal position. While the openings 16 and 19 are in registry fuel has been supplied to the cup 49 of the valve 20, and when the piston reaches its normal position the fuel may be driven into the cylinder and exploded by the compressed air passing through the conduit 50.

30 The advantage of directing radially the exploded gas into the turbine formed by the vanes 22 of the rotor 23, is that the turning effort is applied to all the vanes simultaneously. Although the drawing shows only 35 one outlet for the exploded gases, if desired, more than one can be provided, to eliminate the interference of the exploded gases with the vanes 22.

To start the engine when there is no air 40 pressure in the tank, the cylinder 9 is provided with a priming cap and spark plug combined 57 whereby the necessary few explosions for raising the pressure in the air tanks are obtained. When the desired pressure 45 in the tanks has been obtained the spark plug can be cut out and the engine operated as described.

It is evident that various changes might 50 be made and modifications resorted to in the construction and arrangement of the parts described, without departing from the spirit and scope of my invention; hence I do not wish to limit myself to the exact construction shown.

55 Having thus described my invention, I claim as new and desire to secure by Letters Patent:

1. In an engine, a stator, a rotor, a cylinder associated with said stator and axial with said rotor, a piston in said cylinder forming a fuel-mixture chamber with said cylinder, pneumatically operable means for restoring said piston to normal position, a rotary compressor formed by said stator and 60 rotor, the air pressure from which is adapt-

ed to supply the fuel to said chamber and explode the same therein, valves controlling the supply of air from the compressor to said pneumatically operable means, means connecting said valves to the piston whereby when said piston is moved by the explosion in said cylinder the supply of air from the compressor to said pneumatic means is cut off, said cylinder having openings adapted to register with the openings of the piston when said piston is moved by the exploded fuel, whereby the exploded fuel passes from said chamber to said rotor.

2. In an engine, a stator, a rotor, a cylinder associated with said stator and coaxial with said rotor, a piston in said cylinder forming an explosion chamber therein, said rotor and stator having means forming an air compressor, the air pressure of which is adapted to supply a fuel mixture to said chamber and explode the same therein, whereby said piston is moved in said cylinder, and means actuated by the air pressure from the compressor for restoring the piston to its normal position, said piston and cylinder having openings adapted to register when said piston is moved by the exploded fuel, whereby the exploded fuel is directed radially from said chamber into said rotor substantially as and for the purpose set forth!

3. In an engine, a stator, a rotor, a cylinder associated with said stator, a piston in said cylinder forming an explosion chamber therewith, said rotor and stator having means forming an air compressor, the air pressure of which is adapted to supply a fuel mixture to said chamber and explode the same therein, pneumatically actuated means associated with the piston and said air compressor for restoring the piston to its normal position after the same has been moved by the exploded mixture, and a valve controlling the connection of said pneumatically operable means with the compressor for cutting off the supply of air to said pneumatically operable means during the movement of the piston under the action of the exploded mixture, said piston having means for directing the exploded mixture from said chamber to said rotor, substantially as described.

4. In an engine, a stator, a rotor, a cylinder associated with said stator, a piston in said cylinder forming an explosion chamber therewith, said rotor and stator having means forming an air compressor, the air pressure of which is adapted to supply a fuel mixture to said chamber and explode the same therein, whereby said piston is displaced in said cylinder, pneumatically operable means associated with the compressor and the piston whereby the piston is returned to its normal position after being moved by the exploded mixture, and means

- for interrupting the influence of the compressor on said pneumatically operable means when the piston is moved by the exploded mixture, said piston having means for directing the exploded mixture from the chamber to said rotor in a radial direction to all parts of said rotor.
5. In an engine, a stator, a rotor, a cylinder associated with said stator and axial with said rotor, a piston in said cylinder forming an explosion chamber therewith, said rotor and stator having means forming an air compressor the air pressure of which is adapted to supply a fuel mixture to said 10 chamber and explode the same therein, whereby said piston is displaced within said cylinder, a piston rod associated with said piston, a spider carried by said piston rod, plungers carried by said spider, air pockets 15 engaged by said plungers, means connecting the pockets to the compressor, a valve controlling the connection between the compressor and the pockets, and means for operating the valves associated with the spider 20 whereby pressure on said plungers is cut off when the piston is moved within the cylinder by the explosion of the fuel mixture, said piston and cylinder having openings 25 adapted to register when the piston is moved to its limit position by the explosion of the fuel in the cylinder whereby the exploded fuel is directed radially from said chamber into said rotor, substantially as and for the purpose set forth.
- 30 6. In an engine, a stator, a rotor, a cylinder associated with said stator, a piston in said cylinder forming an explosion chamber therewith, said rotor and stator having means forming an air compressor, means 35 associated with the movement of the piston

adapted to receive a fuel charge under the action of the air compressor when said piston is moved by the exploded fuel, and pneumatically operable means for restoring the piston to its normal position, said charge of fuel carried by said charge receiving means being adapted to be forced into said cylinder by the compressor when said piston is returned to its normal position by said pneumatic means, said piston having means for 45 directing radially the exploded charge to the rotor substantially as and for the purpose set forth.

7. In an engine, a stator, a rotor, a cylinder associated with said stator, a piston in 50 said cylinder forming an explosion chamber therewith, said rotor and stator having means forming an air compressor the air pressure of which is adapted to supply a fuel mixture to said chamber and explode 55 the same therein, pneumatic means associated with said piston and compressor for restoring said piston to its normal position after the same has been displaced by the exploded mixture, said piston and cylinder 60 having openings adapted to register when said piston is moved by the exploded fuel to its limit position, whereby the exploded fuel is radiated from said chamber into said rotor, and means for scavenging the cylinder 65 associated with the compressor and becoming operable when the openings of the piston and cylinder are in register.

In testimony whereof I have signed my name to this specification in the presence of 70 two subscribing witnesses.
